GAME BOARD OR THE LIKE

Robert C. Johnson, 613 Easton Road, Pearisburg, Va.

Filed June 7, 1965, Ser. No. 85,591

Term of patent 14 years

(Cl. D34—5)

Fig. 1

Fig. 2

FIG. 1 is a top plan view of a game board showing my new design; and

FIG. 2 is an end elevational view of the same.

The dominant features of the design reside in the portions shown in full lines. Portions of the design are cross hatched or stippled to indicate contrasting shades.

I claim:

The ornamental design for a game board or the like, as shown and described.
